SAMUEL A. KINSEY, JR., OF PEORIA, ILLINOIS, ASSIGNOR TO KINSEY & MAHLER CO., OF PEORIA, ILLINOIS, A CORPORATION OF ILLINOIS.

VACUUM-VALVE.

1,164,098.

Specification of Letters Patent. Patented Dec. 14, 1915.

Application filed March 23, 1912. Serial No. 635,673.

To all whom it may concern:

Be it known that I, SAMUEL A. KINSEY, Jr., citizen of the United States, residing at Peoria, in the county of Peoria and State of Illinois, have invented certain new and useful Improvements in Vacuum-Valves; and I do hereby declare that the following is a full, clear, and exact description of the invention, which will enable others skilled in the art to which it appertains to make and use the same.

This invention relates to improvements in valves.

It pertains particularly to a vacuum valve or a valve adapted to operate automatically for permitting return of air to a vessel being placed under vacuum to prevent it from collapsing, if for any reason the process of removing the air is carried too far.

The invention has for its object to provide a device of this class in which the valve and valve-seat are set high up within the structure to carry them away from and protect them from strains such as would cause leakage. Valves, particularly those for use with air, leak much more easily than those designed for carrying fluids consequently more care is required to protect them.

It has been customary heretofore in constructing vacuum valves to place the movable part and its seat inside of the threaded part which screws into the vessel-wall or other part that is to receive it. It is well known that a threaded part in the form of a shell is very easily distorted by the presence of grit or dirt or particles of metal such as portions of a thread or "turnings." Now, when the seating parts of the valve lie within the shell and distortion takes place the utility of the valve is immediately destroyed.

An important object of my invention, therefore, is to provide a structure in which the movable part and its seat are placed well up in the body of the device quite remote from the threaded part where there will be no danger of strains of the kind mentioned.

Another object is the provision of a vacuum valve comprising two parts wherein the movable valve-part, the valve-seat and the valve-stem are all carried in a part entirely separate from that which is directly secured in the vessel or member in which the valve is to be carried, so that the parts cannot pos-

sibly sustain any damage such as would result in making the fixture useless.

Another object is to provide a vacuum valve of a peculiar structure in which the air inlet openings are so arranged that foreign matter cannot get into the working parts and cause trouble in preventing the valve seating properly.

Another object is to construct a device of this type in which the valve, in case it becomes separated from the parts that hold it, cannot drop through into the machine or part which carries it.

The invention, besides the above, relates to certain novel structures and arrangement of parts in a vacuum valve and these will be brought out in the description and drawing and pointed out in the claims.

In order to make my invention clearly understood I have provided the accompanying drawing, in which:

Figure 1 is an elevation of my improved valve. Fig. 2 is a plan of a portion of the valve showing part in section, taken on line $\alpha\alpha$, Fig. 1. Fig. 3 is a vertical section of the valve on line YY , Fig. 2. Fig. 4 is a sectional elevation of a portion of the valve on line ZZ , Fig. 2.

Before entering upon a detailed description of the device, I shall again speak of the structure as ordinarily used in vacuum valves in order to better bring out the advantage of mine. As was stated at the outset, the valve and valve-seat have been located in or near the threaded member which screws into the machine or part which is to carry the valve. Now, even though the metal in which the valve seat is formed may be quite heavy, a particle of dirt or metal, or other foreign matter, however small, if caught in the threaded portions results in springing the seat and rendering the valve leaky. Also in constructing a device of this kind, having an opening or openings at the top, foreign matter can readily drop into it and in lying upon the valve seat would, perhaps, prop the valve open or get into the machine on which the device is mounted.

Again, in devices of this kind the structures are such that the valve, if it becomes detached from the parts that hold it, often drops into the machine or tank on which the device is mounted creating considerable damage besides destroying the immediate

utility of said device in that an outflow of the liquid material contained in the machine or tank is prevented. These several faults have necessitated, therefore, a different structure, or one such, for example, as is shown herein. It includes a shell A having a large outer and an inner small end, the latter being exteriorly threaded as at B and adapted to be screwed at its said small or inner end into the threaded opening of a vessel machine or fixture indicated at C which is to carry it. Said shell at its outer or large end is internally threaded to receive a body-portion indicated at D which carries the valve parts. This portion D is provided with any usual flange E to bear upon the upper surface of said part or shell A, said flange being preferably provided with flat faces, as shown in Fig. 1, to receive a wrench. The shell A is also provided with flat faces, as indicated at F in said Fig. 1, and thereby the parts can be readily connected. Said portion D is partially hollow, being open at its upper end but closed at its lower end by a diaphragm G provided with a bore H. Within it is cast a substantially central part J provided with a bore K axially coincident with the bore H of the diaphragm and serving as a guide for the valve-stem L of the valve M. The latter includes a body-portion having a conical upper part N adapted to enter the conical valve-seat of the diaphragm G described, as clearly shown in Fig. 3.

The part J is connected with the walls of the cylinder by radiating vanes O, clearly shown in Fig. 2, one of which is shown in section in Fig. 3 and another in Fig. 4. Cast also with the vanes and the guide is an upper disk-like portion P overhanging the passages between the vanes. This portion P prevents foreign matter from dropping into and through the device or from lodging on the valve seat and interfering with the valve as might result if the passages were left open at the top. The central part J at its lower end is spaced above the diaphragm G so that the air passages between the vanes O can communicate with the shell A through the said bore H.

The valve stem extends some distance above the top of the device and surrounding it is a spring Q one end resting in socket S, for example, in the part P, the other end bearing upward against the head of a screw R carried on the top of the said stem. The adjustment of the screw may provide for any desired tension upon the spring, or the spring may be of a certain desired strength so as to resist a certain pressure thereon. In either case, the valve may be set to permit the passage of air at any desired or given number of inches of vacuum.

While the foregoing describes the preferred structure, I may make slight changes

therein but such as will fall within the meaning and intent of the invention. It is seen that one of my purposes is to provide a vacuum valve in which the valve and valve-seat are entirely removed from any chance of outside forces tending to destroy the proper seating of the said valve. Further it is seen that another purpose is to place the seat and the valve and valve stem in a single integral part so that the valve cannot but seat perfectly.

Attention is directed to the fact that the interior diameter of the lower end B of the shell A is much less than the diameter of the valve M so that if the latter drops down from any cause it cannot pass through the shell but, instead, will lodge therein. The stem of the valve is longer than the distance the valve could possibly descend so that it cannot leave said guide and can be easily raised into place. Or the flow and pressure of the liquid within the machine, or other part, C, will force the valve back upon its seat and hold it there so that the danger of flooding already mentioned herein is avoided. This advantage makes the valve of particular value as will be readily seen.

In my structure there are but two parts to the main structure *i.e.* the parts A and D, the latter having the integral part J as the guide for the valve stem, and thus while yielding all of the advantages named the device is simple and can be produced at a low cost.

I am apprised of a socalled "safety plug" used in connection with internal pressure apparatus but it is so constructed and is so used that it in fact requires no seat for its so called valve, which is merely a plunger acted on by pressure to puncture a soft metal disk as an alarm to an attendant; the plunger merely acting to close the outlet temporarily or until the pressure within the apparatus is relieved by said attendant whereupon the soft metal disk is replaced by another. This device serves an entirely different purpose from a valve, and its said plunger is not required to seat pressure tight.

In a valve to operate with a vacuum apparatus it is required that the movable part shall seat absolutely tight so as to maintain a perfect vacuum within the apparatus. That is to say, it must maintain the required vacuum without change in order that said apparatus may properly perform its work. Furthermore, the movable part or valve must be so arranged as to move inward to let air pass should the vacuum become too great.

The valve must be protected from strains and changes in the form of its seat due to heat or other causes and must therefore lie up within the main body away from all influences and must be protected from dirt or other foreign substance. This advantage is found in my device and to my knowledge

a vacuum valve having my structure and consequent advantages has not been employed.

Having thus described my invention, I
5 claim:

1. A valve structure comprising a body-portion having a recess opening through one end of the same, said body-portion including a wall at its other end having an opening 10 constituting a valve-seat and including also a tubular part within the recess and spaced from the walls of the same, the bore of said part being axially coincident with the said opening, and spaced at its end 15 therefrom, a disk-like portion at the other end of the part, the plane of which lies substantially perpendicular to the bore of said part, and spaced from and overhanging the said open end of the body-portion, and a 20 valve normally closing the opening in the wall and including a stem extending through said opening and lying within the said tubular part.

2. A valve structure comprising a body portion open at one end and including a wall at the other end having an opening consti-

tuting a valve-seat and including also a tubular part whose bore is axially coincident with the said opening, said part being spaced from said wall and having a disk-like portion at its other end lying perpendicular to the bore of said part and spaced from and overhanging the said open end of the body portion, and a series of vanes connecting the tubular part with the shell, there being 30 spaces between said vanes communicating with the opening of the said wall and with the space between the described disk-like portion and the body portion, and a valve normally closing the opening in the wall and 35 including a stem extending through said opening and lying within the said tubular portion, the diameter of said stem being less than that of said opening, in combination with a shell attached to the body portion at 40 that end having the valve.

In testimony whereof I affix my signature, in presence of two witnesses.

SAMUEL A. KINSEY, JR.
